UNITED STATES PATENT OFFICE.

JACK HAGERTY, OF TOLEDO, OHIO.

ALLEY-PIN-CLEANER HOLDER.

Application filed September 15, 1924. Serial No. 737,693.

To all whom it may concern:

Be it known that I, JACK HAGERTY, a citizen of the United States, and a resident of Toledo, in the county of Lucas and State of Ohio, have invented a new and useful Alley-Pin-Cleaner Holder, which invention is fully described in the following specification.

My invention has for its object to provide a holder for rotatable bodies while they are being brushed or rubbed by a abrasive member, whereby the bodies will be rotated and all parts of the surfaces of the bodies will be thoroughly operated upon or treated. The invention is particularly advantageous for holding rotatable bodies while being operated upon by power driven brushes. The preferred embodiment of the invention is used for rotatably supporting alley pins in a horizontal position and so that a rotatable electrically driven alley brush may be placed on the pins to cause the pins to rotate at a speed very much less than the peripheral speed of the brush, owing to the differential speeds of parts of the brush as measured radially from the axis of rotation of the brush and according to the proportionate part of the pin that is located on one side or the other of the axis of rotation of the brush. This will cause the bristles of the major portion of the brush to abrasively act upon or brush or rub the surfaces of the pins.

The invention may be contained in structures of different forms. To present a practical application of the invention I have selected a holder that is a preferred embodiment of the invention as an example of structures containing the invention and shall describe it hereinafter. The holder selected is shown in the accompanying drawings.

Figure 1 is a top view of the alley brush that may be used for cleaning the pins and a top view of the holder. Figure 2 is a view of a section taken on the line 2-2 indicated in Fig. 1. Figure 3 is a view of a section taken on the plane of the line 3-3 indicated in Fig. 1. Figure 4 is a broken view showing parts of the holder folded together. Figure 5 illustrates one of the inserts that may be used for supporting the pins at their necks.

The holder for supporting the pins may be constructed of any suitable material. In

the form of structure shown, the holder is made of sheet metal that may be suitably bent to shape to properly support the pins and contain the brush so as to prevent the brush from slipping from the holder. The holder is particularly designed for supporting the pins in such a position that they may be cleaned by any well known alley brush commonly used in alley courts. In the form of construction shown, the holder 1 is provided with a marginal vertical flange 2 and a narrow platform 3, also located along the perimeter of the holder. A wider platform 4 is located at one end of the holder for supporting the brush while the pins are being removed or inserted in position. The platform 4 forms a convenient means for receiving the brush preparatory to its being used for cleaning of the pins. The planes of the platforms 3 and 4 are preferably slightly below the plane of the upper portions of the sides of the pins. Thus the rotatable alley brush 5, which is electrically driven by a motor located in the housing 6, may be easily pushed from the platform 4 on to the pins by the handle that is commonly connected to the housing 6. The brush 5 may thus be moved back and forth and right to left over the pins in the cleaning operation, the marginal flange 2 operating to prevent the brush from slipping entirely from the holder.

The pins 7 are provided with holes 8 formed in the making of the pins, for centering the pins relative to the lath on which they are formed. A bar 9 is secured at its ends to the holder and is provided with a plurality of cross pins 10 that are secured in properly spaced relation to permit the pins 10 to enter the holes 8 of the bottoms of a plurality of pins disposed in parallel relation, and thus rotatably support the bottom ends of the pins. The head ends of the pins may be rotatably supported by means of the bars 11. The bars 11 are provided with a plurality of substantially semi-circular recesses 12 in which the necks of the pins may be inserted and which will retain the alley pins in position on the pins 10 notwithstanding the rotative movements induced in the alley pins. Thus the alley pins may be readily placed in the holder by mere insertion of the pins 10 in the bottoms of the alley pins and dropping the necks of the pins in the recesses 12. If desired, the recesses 12

may be formed in inserts 13 of any suitable material, preferably of such a character that rings will not be formed by rubbing of the pins on the inserts. Thus the bearing surface 14 of the insert may be curved so as to conform substantially to the curvature of the neck at the point where it joins with the body portion of the alley pin to prevent any ringing of the neck of the pin by means of its rotation. When, therefore, the rotating 10 alley brush 5 is pushed from the platform 4 over the pins, the rotation of the brush will cause a rotation of the pins at a speed which differs very materially from the different speeds of portions of the brush. As 15 is well known, the portions of the brush near its periphery will move at a very much greater speed than the portions near the axis of rotation, and also the movement of portions 20 on one side of the axis of rotation of the brush is in one direction while the movement of portions of the brush located diametrically on the opposite sides is in the opposite direction. Also the diameters of 25 different portions of the pins vary, the body portion having a diameter much greater than the neck or head portion. Thus the pins will rotate according to the relative position of the axis of the brush and according to 30 the diameters of the portions of the pins that make contact with the brush. The speed of rotation of the pins will consequently be the resultant of these various components, and the brush will effectively rub and brush all parts of the surfaces of the pins to 35 efficiently clean the pins.

If desired, the holder may be so constructed that it may be folded for convenience of handling and storing the holder. The 40 holder may be formed of two parts 15. One end of the bar 9 may be located between the two parts of the platform 4. The parts 15 may thus be hingedly connected to the bar. The bar 9 is provided with arms 16 located 45 at its ends. The arms 16 may be riveted or otherwise secured to the ends of the bar 9 and hingedly connected to the parts 15 as by the pintles 17. The arms 16 position the hinging points or axes of the parts relative 50 to each other so that when the parts are folded together, the upper edges of the peripheral flange 2 of each part will contact. The folded holder will thus constitute a compact arrangement that may be easily handled and stored away.

I claim:—

1. A holder for alley pins having a plurality of pins for receiving the bottoms of the alley pins, and a plurality of curved 60 supports to receive and rotatably support the necks of the alley pins, said supports and first mentioned pins being so positioned

that the alley pins may be supported in approximately a horizontal plane.

2. In a holder for alley pins, two rows 65 of horizontally extending pins for receiving the bottoms of alley pins, and two rows of curved supports for receiving and rotatably supporting the necks of the alley pins, said several rows being so arranged that the 70 head ends of said alley pins extend in opposite directions.

3. In a holder for alley pins, a member having a plurality of pins extending from opposite sides of the member and in a substantially horizontal plane and a pair of members one adjacent each pin carrying side of first named member having substantially semi-cylindrical recesses located in alignment with the pins for rotatably supporting the alley pins so that their axes will be substantially in a horizontal plane, the pins extending into the bottoms of the alley pins and the necks of the pins located in the recesses. 80

4. A holder for alley pins, the holder having two hingedly connected sections, a bar located between the sections of the holder and having pins protruding from opposite sides of the bar in a substantially horizontal plane, bars forming parts of the sections of the holder and having recesses for supporting the alley pins, said bars being arranged on opposite sides of said first bar. 90

5. In a holder for alley pins, a member having a plurality of pins extending from opposite sides of the member and a pair of members having substantially semi-cylindrical recesses located in alignment with the pins for rotatably supporting the alley pins so that their axes will be substantially in a horizontal plane, the pins extending into the bottoms of the alley pins and the necks of the pins located in the recesses, a platform located at one end of the holder, the top of the platform being located in a plane slightly below the tops of the alley pins for supporting a rotatable abrasive member. 100

6. In a holder for alley pins, the holder having two hingedly connected sections, a bar located between the sections of the holder and having pins protruding from opposite sides of the bar and in a substantially horizontal plane, bars forming parts of the sections of the holder and having recesses for receiving the necks of said alley pins, said last mentioned bars being positioned on opposite sides of said first bar. 110 platforms on said sections for supporting a rotatable abrasive member in a plane slightly below the tops of the alley pins. 115

In testimony whereof I have hereunto signed my name to this specification.

JACK HAGERTY,
